(57) **CLAIM**

The ornamental design for a beverage insulator as shown and described.

DESCRIPTION

FIG. 1 is a top perspective view of a beverage insulator showing my new design in a condition of use;

FIG. 2 is a top perspective view thereof;

FIG. 3 is a bottom perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

The dash-dot-dash broken lines illustrating a pull tab can and golf tees in FIG. 1 are for the purpose of illustrating the beverage insulator in a condition of use and form no part of the claimed design. The remaining dash-dot-dash broken lines depict portions of the beverage insulator that form no part of the claimed design. The dash-dot-dash broken lines depict stitching that forms no part of the claimed design. The dash-dot-dot-dash lines illustrate boundaries that form no part of the claimed design.
